Primary Examiner — Clare E Heflin(74) *Attorney, Agent, or Firm* — Jeffrey T. Stover, Haynsworth Sinkler Boyd, P.A.(57) **CLAIM**

The ornamental design for a lighting fixture, as shown and described.

DESCRIPTION

FIG. 1 is a bottom perspective view of a new lighting fixture; FIG. 2 is a top perspective view thereof; FIG. 3 is a front elevation view thereof; FIG. 4 is a back elevation view thereof; FIG. 5 is a left side elevation view thereof; FIG. 6 is a right side elevation view thereof; FIG. 7 is a top plan view thereof; and, FIG. 8 is a bottom plan view thereof.

The broken line disclosure in the views represents environmental structure which forms no part of the claimed design.

1 Claim, 8 Drawing Sheets(56)
